UNITED STATES PATENT OFFICE.

JAMES B. HAGUE, OF NAPOLEON, OHIO.

DIE FOR FORMING SECTIONAL HORSESHOES.

SPECIFICATION forming part of Letters Patent No. 364,244, dated June 7, 1887.

Application filed January 7, 1887. Serial No. 223,686. (No model.)

To all whom it may concern:

Be it known that I, JAMES B. HAGUE, a citizen of the United States, residing at Napoleon, in the county of Henry, State of Ohio, 5 have invented certain new and useful Improvements in Dies, of which the following is a specification, reference being had therein to the accompanying drawings.

This invention relates to improvements in dies; and it consists in so making the parts of the die as to form a horseshoe in two parts and a coupling to join them, and to provide for the overflow of the metal.

In the drawings, Figure 1 is a view of the 15 meeting faces of the die for forming one half of the shoe, and Fig. 2 is a view of the meeting faces of the die for forming the other half of the shoe and the coupling-piece. Fig. 3 is a view of the separate parts of the shoe.

20 The anvil-die A is provided upon the meeting face with the slot B. The said slot is provided at the one extremity with the inwardly rounded end C. At the other extremity is an elongated and deepened slot, D, which forms 25 the heel-calk of the shoe. Extending from the bottom of the said slot B, and near the outer edge, is a ridge, E, which is provided with pointed projections at regular intervals, to form, in conjunction with the hammer-die, the 30 nail-holes of the shoe. At the extremity of the said slot having the impression for the heel-calk, and in the face of the die, is a small channel, F, leading from the said slot to outside the dies. The face of the die next to the 35 inner edge of the said slot is beveled down, substantially as shown, to near the bottom of the said slot.

The hammer-die A' is provided, at a point over the center of the slot B in the anvil-die and 40 near the curved end, with the round projection G, which, when the faces of the die come together, rests upon the bottom of the said slot and forms a hole in the shoe for the rivet of the coupling. Upon the face of the said die, and over the 45 projections upon the ridge E, are the small projections E', which rest upon the corresponding projections in the anvil-die and form the nail-holes of the said shoe.

50 Directly over the impression D in the anvil-die is the impression D', which forms the guard on the shoe to prevent the shifting of the same.

Upon the said die is a ridge-like projection, K, being directly over the bevel on the anvil-die. The inner face of this ridge is beveled to correspond to the said bevel on the anvil-die, and the outer face is beveled away to near the projections E'. 55

The die as shown in Fig. 2 is in all respects the same, with the exception of the curve of the slot B and the rounded end, which is 60 rounded outwardly instead of inwardly. The said ends have the same size curve, so that they will work together as a hinge. In the anvil-die of the pair shown in Fig. 2 is an impression, H, of the coupling-piece for the shoe. 65 To either side of the center of the said impression are two projections, I, similar in size to the projections G, and for the purpose of forming perforations in the said coupling-piece similar to those in the ends of the halves of the 70 shoe. Leading from the said impression to the outside of the die is a small channel, J. Upon the hammer-die and over the projections I are two small projections corresponding in size to the said projections, and resting 75 upon them when the hammer is down.

In operating these dies the metal is roughly prepared to correspond to the curve of the slots B and the impression H, and placed in their respective impressions while hot. The 80 hammers bearing the dies A' are brought down upon the metal while in this heated condition. The metal, being soft, is driven down into the impressions and forced to take the shape of the same. The ridge E forces its way into the 85 metal and leaves an impression in the same to receive the heads of the nails; and the projections upon the same, in conjunction with the projections E' upon the hammer-die, form the holes in the metal for the nails to pass through. 90 The projections G operate as punches, and form in the metal the holes for the rivets used in coupling the two halves of the shoe. When the dies come thus together, the ridge K forces down upon the metal, and the outer bevel of 95 the same forces the metal to the center. This displacement, together with that of the ridges E and projections G, forces the metal into the impressions D and D'.

The operation regarding the coupling-piece 100 is the same as that just described, the hammer-die forcing the metal down into the impres-

sion H and the projections I, forming the rivet-holes used in coupling. If in this operation there is too much metal in the dies, it will run off at the small channels F and J and form a handle, whereby the shoe can be extracted from the said dies.

5 What I claim is—

In dies for horseshoes, such as described, the combination of the anvil-die A, provided 10 with the slot B, said slot having an inclined surface at its inner edge, and the hammer-die

A', provided with the projection K, said projection having an inclined surface corresponding to the said inclined surface in the slot B; substantially as and for the purpose set forth. 15

In testimony whereof I affix my signature in presence of two witnesses.

JAMES B. HAGUE.
